UNITED STATES PATENT OFFICE

FRANK SBICCA, OF PHILADELPHIA, PENNSYLVANIA, ASSIGNOR TO SBICCA-METHOD SHOES INCORPORATED, OF PHILADELPHIA, PENNSYLVANIA, A CORPORATION OF DELAWARE

METHOD OF PRODUCING COMPLEMENTARY INSOLE-OUTSOLE COMBINATIONS

Application filed November 7, 1931. Serial No. 573,676.

REISSUED

This invention relates to complementary insole-outsole combinations and to a method of producing the same.

In the production of light soled shoes, it has been proposed to employ an outer sole having a rand removed from the ball section thereof and having the heel and shank portions thereof reduced in thickness together with an insole comprising a rand portion to fit about the margins of the projection thus left upon the upper surface of the outer sole and an attached shank. These combinations have, however, been separately produced; that is to say, the rand removed from the outer sole and the material removed from the shank and heel of the outer sole in reducing the thickness thereof are waste material and the material removed from the central portion of the ball section of the inner sole is likewise waste material. For this reason, previous shoe making methods involving the use of complementary insole-outsole combinations of this character have been relatively expensive to produce. Furthermore, they prove unsatisfactory in that it is practically impossible to provide for an accurate fit between the insole and outsole when they are placed together in the manufacture of the shoe. Additionally, it is necessary that special tools be provided in the formation of the inner sole.

In a prior application, Serial No. 512,965, filed February 2, 1931, for shoe and method of making the same, patented December 29, 1931, No. 1,838,708, I have described a method of constructing such shoes which eliminates objections to the method above referred to, to the extent that the rand removed from the outer sole is employed in the construction of the shoe and instead of employing an inner sole blank which is of full length, a blank is provided which is merely a shank piece to which the ends of the rand are secured. My prior method, furthermore, eliminated those objections to the ordinary insole-outsole combinations based on the failure of the rand portion of the insole to properly fit about the marginal portions of the sole, but still involved the loss of material removed from the shank and heel portions of the outer sole

and the necessary cost of the shank piece of the inner sole.

An important object of the present invention is the provision of a method of producing complementary insole-outsole combinations in which all waste is eliminated and an absolute fit assured between the insole and outsole in the completed shoe. 55

A further object of the invention is the provision of a method of producing such combinations which may be readily carried out at the factory and by use of machines commonly employed at the factory with but slight modifications thereof. 60

These and other objects I attain by the construction shown in the accompanying drawings wherein, for the purpose of illustration, I have shown a preferred embodiment of my invention, and wherein:

Figure 1 is a plan of a shoe blank illustrating the same as split in the performance of one step of the process; 70

Fig. 2 is a side elevation of the blank of Fig. 1;

Fig. 3 is a plan of the blank channeled in the performance of a second operation; 75

Fig. 4 is a plan of the blank showing a further channelling operation;

Fig. 5 is an enlarged section on the line 5—5 of Fig. 4; 80

Fig. 6 is a fragmentary section on the line 6—6 of Fig. 7;

Fig. 7 is a plan of the blank illustrating a still further step in the process, the arrows indicating the movement of the splitting knife; 85

Fig. 8 is a side elevation of the blank of Fig. 7 after completion of the splitting process illustrated therein;

Fig. 9 is a top plan of the outer sole; and 90

Fig. 10 is a bottom plan of the inner sole.

Referring now more particularly to the drawings, the numeral 10 generally designates a sole blank having flesh and grain sides indicated respectively at 11 and 12. This blank in the production of the combination is passed through the following steps which while given in a preferred order, may obviously be interchanged in the order in which they are described. 95

A split 13 is formed in the blank 10, this split paralleling the flesh and grain sides of the blank and extending from the rear end of the heel of the blank to a transverse line 14 at the junction of the ball and shank sections of the blank. A rand 15 is then separated from the margin of the ball section of the shoe at the flesh side thereof, this rand being removed by a combination of horizontal and inclined channel cuts 16 and 17, of which the horizontal channel forms a continuation of the split 13 extending inwardly from the blank margins a predetermined distance and extending entirely about the ball section. The inclined channel extends about the margins of the ball section of the blank and is directed downwardly and outwardly from the flesh side of the blank, terminating at its lower end at the inner end of the horizontal channel 16. The inclined channel has a branch 18 extending between the inner ends thereof from the flesh side of the sole inwardly and downwardly, the inner lower end thereof coinciding with the forward end of the split 13 so that the insole blank is severed from the outer sole entirely about the projection A formed on the ball section of this sole. These operations completely free the insole and it will be obvious that the insole and outsole must be absolutely complementary and will, accordingly, interfit perfectly in the assembly of the shoe. Additionally, it will be noted that there is no waste whatever in the production of the insole-outsole combination, the insole comprising merely those portions of the flesh side of the blank removed in the formation of the projection A upon the upper surface of the outer sole.

The process employed in the production of shoes by use of combinations of this character is preferably that set forth in my prior application above identified, but may obviously be employed in the production of other shoes, as for example, shoes produced by processes similar to that described in the patent to J. A. Kelly, granted August 31, 1926, No. 1,597,685, for art of making shoes.

Since, as hereinbefore noted, the particular order of the steps employed in the production of the insole is immaterial, it is to be understood that I do not wish to be limited to the order of recitation thereof in the appended claims.

I claim:

1. The method of producing complementary insole-outsole combinations comprising the following steps, providing a leather sole blank of the desired thickness of the outsole and having a grain and a flesh side, splitting the heel and shank portions of the sole blank to form insole and outsole shank pieces, removing a rand from the margin of the ball section of the flesh side of the sole while leaving the same attached to the forward end of the insole shank piece, and splitting

the sole between the shank and ball sections by a cut extending inwardly from the flesh side thereof to the depth of the desired insole and between the rand terminals.

2. The method of producing complementary insole-outsole combinations comprising the following steps, providing a leather sole blank of the desired thickness of the outsole and having a grain and a flesh side, splitting the heel and shank portions of the sole blank to form insole and outsole shank pieces, removing a rand from the margin of the ball section of the flesh side of the sole while leaving the same attached to the forward end of the insole shank piece and cutting inwardly from the flesh side of the sole blank to a depth equal to the thickness of the desired insole and on a transverse line extending from terminal to terminal of the rand.

3. The method of producing complementary insole-outsole combinations comprising the following steps, providing a leather sole blank of the desired thickness of the outsole and having a grain and flesh side, splitting the heel and shank portions of the sole blank to form insole and outsole shank pieces, removing a rand from the margin of the ball section of the flesh side of the sole while leaving the same attached to the forward end of the insole shank piece and forming a cut extending transversely from terminal to terminal of the rand and inwardly from the flesh side of the blank to the forward end of the split severing the heel and shank portions of the blank.

4. A unitary insole having an internally bevelled marginal frame at its ball section, said insole comprising the flesh side of a sole blank from which a unitary outsole has been removed, said insole having its lower surface including said bevelled marginal wall of said frame exactly complementary to the upper surface of the removed outsole.

FRANK SBICCA.
